UNITED STATES PATENT OFFICE.

JAMES L. ANDERSON, OF BAYONNE, NEW JERSEY, ASSIGNOR, BY MESNE ASSIGNMENTS, TO AIR REDUCTION COMPANY, INCORPORATED, OF NEW YORK, N. Y., A CORPORATION OF NEW YORK.

WIRE-FEEDING DEVICE.

Application filed February 17, 1920, Serial No. 359,463. Renewed March 13, 1922. Serial No. 543,459.

To all whom it may concern:

Be it known that I, JAMES L. ANDERSON, a citizen of the United States, and resident of Bayonne, in the county of Hudson and 5 State of New Jersey, have invented a new and useful Wire-Feeding Device, of which the following is a specification.

The object is to provide a simple, compact and effective wire-feeding means for 10 welding torches. To this end the invention comprises the unitary supporting and feeding device, hereinafter described in its preferred embodiment and more particularly pointed out in the appended claims.

15 In the accompanying drawings, forming a part hereof:

Fig. 1 is a side elevation of the invention applied to a torch, which is mounted upon an adjusting bracket;

20 Fig. 2 is an enlarged plan view of the device, omitting the motor;

Fig. 3 is a front view of the device; and

Fig. 4 is a detail perspective view of a part on a still larger scale.

25 The drawing represents an oxyacetylene or like welding torch 1, which is mounted upon an adjusting bracket 2, forming the subject-matter of a separate application. The torch has a cylindrical stock 3 and a 30 tip 4 containing passages 4^a from which the flame jets are delivered.

On the upper part of the torch stock, above the bracket, is a clamp 5 for supporting the wire-feeding means. The clamp 35 comprises two parts, each comprising a portion of two laterally united collars 6, 7 and a connecting web 8. The collar 6 is relatively small, to embrace the torch stock, and the collar 7 relatively large to receive a

40 cylindrical electric motor 9. The two pieces of the clamp are united by screws 10 passing through the webs 8, the relations being such that when the collars are thus assembled their ends 11 are separated, so that 45 they may be drawn together resiliently by screws 12 upon the stock and motor.

The motor may thus be supported at the front and somewhat to one side of the stock of the torch, with its armature shaft 14 projecting downwardly. The motor is provided with a known speed-regulator 15.

50 A bracket 16 projects downward from the torch-clamping portion of one of the halves of the clamp, and another bracket 17 from

the motor-clamping portion of the other 55 half. A supplementary bracket piece 18 is applied to the inner face of a hub 19 on the lower end of the bracket 16, said piece having a transverse opening and a projecting bushing 20, which latter passes through the 60 hub and is engaged at the outer side thereof by a clamping nut 21. A transverse shaft 22 is journaled in said bushing and in another bearing in the bracket 17, and bears a knurled feed roller 23 adjacent the 65 bracket piece 18, and a worm-wheel 24 in position to mesh with a worm 25 on the lower end of the armature shaft.

The bracket piece 18 also has another transverse opening 26 in which, by nut 27, 70 is secured the stub journal of a grooved guide roller 28, peripherally opposite the feed roller 23. Lugs 29, 30 projecting inward from the bracket piece above and below the rollers contain openings 31 in line 75 with the interval between the rollers. Sections of a guide tube 32 are secured at their adjacent ends in these openings, the lower section extending downward to the torch tip 4, where its lower end is secured at the 80 entrance of a wire duct 33 passing through the tip. The wire α from a suitable supply, not shown, passes through the guide tube and between the rollers, downward to and through the torch tip, where its extremity 85 is continually melted off by the heat of the jets to add itself to the metal of the weld. The construction of the tip with its passages for jets and for the wire, and the combination of the same with means, generally, for feeding wire through the wire passage, form 90 the subject for a separate application.

What I claim as new is:

1. A wire-feed for welding torches comprising a clamp including a torch-embracing 95 portion, shaft bearings and a motor-carrying portion, a transverse shaft in said bearings, a wire-feed roller and a gear-wheel on said shaft, and a motor supported by the motor-carrying portion of the clamp, geared 100 to said gear-wheel.

2. A wire-feed for welding torches, including a clamp comprising torch-clamping and motor-clamping collar portions laterally united with each other, a motor in the 105 motor-clamping portion, and a transverse shaft in the support geared to the motor shaft and bearing a wire-feed roller.

3. A wire-feed for welding torches, including a clamp comprising torch-clamping and motor-clamping collar portions laterally united with each other, a motor in the motor-clamping portion having its shaft projecting downwardly, brackets extending downward from the clamp, and a transverse shaft journaled in said brackets bearing a feed roller and geared to the shaft of the 10 motor.
4. A wire-feed for welding torches, comprising a clamp having a torch-embracing portion and a motor-carrying portion, a motor supported by said motor-carrying portion of the clamp, a bracket on the clamp bearing a guide-roller, a shaft journaled in the bracket bearing a feed-roller opposite the guide-roller, and gearing between said shaft and the motor.
- 20 5. In a wire-feed for welding torches, the combination of a torch clamp, a wire-feed roller carried by the clamp, a motor on the clamp geared to said feed-roller, a bracket piece held fast to the clamp on a pivot permitting its angular adjustment about the 25 axis of the feed roller, and a guide roller carried by said bracket piece peripherally opposite the feed roller.
6. In a wire-feed for welding torches, the combination of a torch clamp, a wire-feed 30 roller carried by the clamp, a motor on the clamp geared to the feed roller, and a bracket piece held fast to the clamp on a pivot permitting its angular adjustment about the axis of the feed roller and carrying a guide roller opposite the feed roller and means for guiding the wire in alinement with the interval between the rollers.

JAMES L. ANDERSON.
